UNITED STATES PATENT OFFICE.

CYRUS F. JONES, OF OREGON, ILLINOIS.

NOTE-SHEET-FEED MECHANISM FOR MUSICAL-INSTRUMENT PLAYERS.

982,277.

Specification of Letters Patent. Patented Jan. 24, 1911.

Application filed May 17, 1909. Serial No. 496,635.

To all whom it may concern:

Be it known that I, CYRUS F. JONES, a citizen of the United States, residing at Oregon, county of Ogle, and State of Illinois, have invented certain new and useful Improvements in Note-Sheet-Feed Mechanism for Musical-Instrument Players, of which the following is a specification.

My invention relates to note sheet feed 10 mechanism for mechanical instrument players.

The object of my invention is to provide means adapted to coöperate with mechanism of the character mentioned whereby the note sheet will be automatically caused to follow a comparatively direct course over the tracker-bar of an instrument of a nature stated so as to effect the correct rendition of the music.

20 A further object is to provide a mechanism of such character which will be effectual in its operation, and strong, durable and comparatively simple of construction.

Other objects will appear hereinafter.

25 With these objects in view my invention consists in a mechanism characterized as above mentioned and in certain details of construction and arrangement of parts all as will be hereinafter fully described and particularly pointed out in the claims.

30 My invention will be more readily understood by reference to the accompanying drawings forming a part of this specification, and in which,

35 Figure 1 is a front elevation of a note sheet feed mechanism in which is embodied the preferred form of my invention, Fig. 2 is a vertical transverse section thereof taken on the line $\alpha\alpha$ of Fig. 1, Fig. 3 is a slightly 40 enlarged rear elevation of the removable portion of the mechanism shown in Fig. 1, Fig. 4 is an enlarged fragmentary detail perspective of an end portion of the tracker-bar illustrating an integral part of my note 45 sheet guide mechanism arranged for operation therewith. Fig. 5 is a detail view illustrating the bar connecting the frame of one roller and the spindle of the other, and, Fig. 50 6 is a detail illustration of the means for securing the tracker bar in position.

Referring now to the drawings 1—1 indicate frame-work brackets secured together in any suitable manner. Slidably mounted upon guide pins 2 secured in and inwardly

projecting from the upper extremities of 55 the brackets 1—1 is a forked frame 3 in the upwardly extending arms 4 of which are journaled the spindles of the usual removable roller 5 upon which is carried or coiled the note sheet to be fed over the instrument 60 tracker-bar. Set screws 6 threaded in the upper end portions of the brackets 1—1, the inner extremities of which are adapted to contact lugs 7 depending from the frame 3 are adapted to limit the free lateral movement 65 of the latter. Having its spindles slidably journaled in the lower portion of the brackets 1—1 is the usual receiving roller 8 upon which is adapted to be coiled the note sheet after its passage over the instrument 70 tracker-bar. A bar 9 fixed as at 10 and 11 to the frame 3 and at 12 to the extremity of the spindle 13 of the roller 8 effects the simultaneous movement of said frame and 75 roller.

14 indicates the usual tracker-bar or duct bridge spanning the brackets 1—1 at a point intermediate the rollers 5 and 8, the same being secured to the brackets 1—1 by screws 15 passing through slots 16 provided in 80 either of the extremities of said bar, said screws being threaded into bosses 17 formed upon the inner surfaces of the brackets 1—1. Arranged upon the inner surfaces of the brackets 1—1, the same being threaded upon 85 screws 18 the heads of which are rotatably mounted in said brackets, hence permitting of independent lateral adjustment thereof, are preferably rectangular blocks 19. Pins 20 are secured in and project outwardly 90 from the blocks 19, said pins slidably resting in perforations provided for the reception thereof in the brackets 1—1 lock the brackets 19 against rotary movement. Secured in and extending through the lower end portions of said blocks 19 are tubes 21. The forward end portions of said tubes are preferably vertically flattened or elongated in form, the same being adapted to travel in the slots 16 of the tracker-bar, the forward 95 extremities of said tubes lying in the plane 100 of the front surface of said tracker-bar, as clearly shown in Fig. 4.

Supported upon a bracket 22 secured to and laterally projecting from one of the 105 brackets 1, is a double pneumatic 23, that is a pneumatic provided with two independent air chambers. An angular connecting

rod 24 having its respective extremities secured to the frame 3 and a yoke 25 which connects the movable outer walls 26 of the pneumatic 23, effects an operative connection between said walls of the latter and the frame 3 and hence the rollers 5 and 8. By such provision it is evident that any operation effecting either of the chambers of the pneumatic to such a degree as to cause the oscillation of the removable wall thereof will cause simultaneously the lateral movement either to the left or right depending upon from which chamber air is exhausted, of the rollers 5 and 8 and hence of the note sheet 15 carried thereon.

The respective chambers of the pneumatic 23 are connected by tubes 27 to separate similar valve chambers 28, the latter being connected by tubes 29 with suction pumps 20 (not shown), it being understood, of course, that the valves of said chamber normally close communication between the chambers of said pneumatic and said suction pumps. Establishing communication between the 25 valve chambers 28 and the rearward extremities of the tubes 21 are tubes 30. The valve provided in each of said chambers 28 is so designed that air drawn through the tube 30 will cause the opening of said valve, such 30 opening of the latter consequently effecting the exhaustion of air from one of the chambers of the pneumatic and hence the collapse of the movable wall thereof.

The operation of the device is as follows: 35 The note sheet to be rendered is coiled upon the roller 5, the free extremity thereof being drawn down over the front curved surface of the tracker-bar and connected in the usual manner to the roller 8, the same being, when 40 the mechanism is in operation, coiled upon the last named roller. The tubes 21 are so adjusted in the tracker-bar that the front openings thereof are just covered by the edges of the note sheet when the latter is in correct 45 position upon the tracker-bar. Now, upon the note sheet swerving in the slightest degree either to the right or left, one or the other of the openings in the tubes 21 will be instantly exposed. Such exposure admits 50 air to one of the valve chambers 28 opening the valve therein, resulting, as before described, in the collapse of one side of the pneumatic, consequently causing the lateral movement of the rollers 5 and 8 and hence 55 of the note sheet to its initial or correct position. By elongating the ends of tubes 21 an opening of considerable area is uncovered upon the slightest swerving of the note sheet thus rendering the apparatus very 60 sensitive. Because of the tubes 21 being adjustably mounted, as before described, it is evident that the same will accommodate note sheets of all widths within ordinary

range. By making said tubes independently adjustable provision is made to accommodate variations in the lines of perforations on the note sheet.

In the operation of the device it might be found that the actuation of only the roller 5 will effect the same results as above described where both the rollers 5 and 8 were actuated. If so found, the yoke 9 may be dispensed with, it being understood that such dispensation may be made without departing from the spirit of my invention.

While I have shown what I deem to be the preferable form of my invention I do not wish to be limited thereto as there might be many changes made in the details of construction and arrangement of parts without departing from the spirit of my invention.

Having described my invention what I claim as new and desire to secure by Letters Patent is:

1. In a device of the class described, the combination of a suitable frame; note sheet rollers mounted in said frame; a tracker-bar; means for shifting the relation between said rollers and tracker-bar; members having openings located adjacent the ends of the tracker-bar and adapted to be covered by the edges of the note sheet when in normal or correct position in the device; means for adjusting said members independently of each other; pneumatic means controlled by the openings in said members; and connections between said pneumatic means and said rollers and tracker-bar arranged to shift the relation between said rollers and tracker-bar to maintain them in correct operative relation, substantially as described.

2. In a device of the class described, the combination of a suitable frame; note sheet rollers mounted in said frame; a tracker-bar; means for shifting the relation between said rollers and tracker-bar; members having openings elongated transversely of, and located adjacent the ends of the tracker-bar and adapted to be covered by the edges of the note sheet when in proper position in the device, said members being adjustable independently of each other; pneumatic means controlled by the openings in said members; and connections between said pneumatic means and said rollers and tracker bar arranged to shift the relation between said rollers and tracker-bar to maintain them in correct operative relation, substantially as described.

3. In a device of the class described, a frame work, guide pins on opposite sides of said frame work, a frame, lugs on said frame perforated to receive said pins which form guides for the same, a roller mounted in said frame, pneumatic means for shifting said

frame with its roller on said pins, a tracker bar and set screws extending through said frame work and adapted to engage said lugs to shift said frame and roller with relation to the tracker bar and to limit the movement of said frame when actuated by said pneumatic, substantially as described.

In testimony whereof I have signed my name to this specification in the presence of two subscribing witnesses.

CYRUS F. JONES.
